UNITED STATES PATENT OFFICE.

SILAS C. MACDOWNNEY, OF CHICAGO, ILLINOIS.

STORE-FRONT CONSTRUCTION.

1,202,550.

Specification of Letters Patent. Patented Oct. 24, 1916.

Application filed February 12, 1914. Serial No. 818,228.

To all whom it may concern:

Be it known that I, SILAS C. MACDOWNNEY, a citizen of the United States, residing at Chicago, in the county of Cook and State of Illinois, have invented certain new and useful Improvements in Store-Front Construction, of which the following is a specification.

My invention relates to building construction in general and particularly to the mounting of plate glass windows in store fronts, and has in view as its principal objects the holding of the glass securely, and also the provision of means for regulating ventilation to prevent the accumulation of condensed moisture upon the glass and for carrying away such moisture and removing accumulated dust from within the ventilating passages.

Other advantageous and novel features of the construction will be made apparent as the description proceeds.

In order that the invention may be readily understood preferred and modified embodiments of the same are set forth in the accompanying drawings and in the description based thereon. Obviously, however, the invention is susceptible of embodiment in other and varied constructional forms and the drawing and description are to be construed in an illustrative and not in an unnecessarily limiting sense.

In the drawings Figure 1 is a perspective view of a portion of a store front construction showing the application of the invention thereto; Fig. 2 is a front elevation of Fig. 1 with the facing and retaining strip removed; Fig. 3 is a vertical section through one of the glass supporting blocks or chairs; Fig. 4 is a similar section taken on a line between two of the chairs; Fig. 5 is a section similar to Fig. 3 through a slightly modified form of construction; Fig. 6 is a front elevation of Fig. 5; Fig. 7 is a section similar to Figs. 3 and 5 illustrating a further modification; and Fig. 8 is a vertical longitudinal section on the line 8—8 of Fig. 7.

In the embodiments illustrated the reference numeral 11 designates the ordinary window sill and 12 the inner stop or front

edge of the flooring adjacent the window. The sill and stop are covered by a protective apron 13 of suitable non-corrosive metal such as copper, whereby the sill and stop if of wood are protected from deterioration 55 which would speedily result if moisture were allowed access thereto.

At intervals along the window sill and also along the sides and top of the window frame, which in this connection are the equivalents of the sill, are arranged a series of glass supporting blocks or chairs 14, which, as applied to the sill, have a substantially horizontal portion 15 forming a seat for the edge of the glass and a substantially vertical 60 back portion 16 against which the glass bears laterally. The chairs 14 are provided with a horizontal aperture for the reception of screws 17 by means of which they are firmly secured to the stop 12 against which 65 the back of the chair abuts.

The chairs having been arranged at intervals around the window opening, as above described, the glass plate is placed in position with its edges bearing against the seats 75 of the chairs and its sides adjacent the edges bearing laterally against the chair backs, as clearly shown in Fig. 1, for example. A facing or retaining strip 18 is then placed exterior to the glass around the margin 80 thereof, which strip has a portion 19 which fits snugly upon the chairs 14 and also marginal flanges 20 and 21, the former of which bears against the outer face of the glass in opposition to the chair back 16, while the 85 flange 21 occupies a vertical position covering the outer edges of the chairs and abutting against the apron 13 upon the sill 11, as clearly shown in the drawing. This facing or retaining strip is firmly secured to the 90 chairs by means of screws 22.

It will be observed that the spaced relation of the chairs 14 provides for passages therebetween and beneath the edge of the glass. The flange 21 of the facing strip 18 95 is also notched at intervals, as indicated at 23, so as to provide access from without to the said passages, whereby air is permitted, for purposes of ventilation, to pass through the notches 23 to the passages and thence 100

upward on the inner side of the glass between the chair backs. Thus the circulation of air maintains a substantially uniform temperature upon both sides of the glass and minimizes the tendency of moisture to condense upon the inner face of the glass.

It is desirable under changing atmospheric conditions to control the ventilation of the window space so as to exclude the dust on 10 windy days and reduce the amount of air interchange in excessively cold weather. It has been usual in constructions of this general character to provide a sliding register member for the outer entrance to the air passages, but this arrangement is inconvenient and has many other disadvantages. According to the present invention I arrange for the control of the ventilation by mounting upon the stop 12 a cap or cover plate 24 which overlies the inner portions of the passages and abuts with its edge against the inner face of the glass so as to effectually exclude the entrance of air or dust when in a closed position. At the sides and top of 25 the window this plate may be permanently fixed in a closed position, but at the bottom of the window, as illustrated, the plate is made readily adjustable by hinging the same to the inner edge of the apron 13 where it 30 overlies the stop 12. As shown in Figs. 1 to 4 inclusive, the hinge comprises a series of staple members 25 which pass through the inner edge of the cover plate. Provision is made for locking the plate in any adjusted 35 position by means of a latch 26 having an enlarged head 27 which engages within a slot 28 of the cover plate 24. The opposite end of the latch 26 being pivoted at 29 to a link 30 which in turn is pivoted at 31 to a 40 standard 32. Upon the pivot 29 is mounted a knurled head 33, by means of which the pivot joint at 29 may be tightened so as to lock the members 26 and 30 together, whereby the plate 24 will be held in adjusted 45 position.

In Fig. 5 a modification of the cover plate mounting is shown in which form of construction the inner edge of the apron 13 is provided with a bead 34 and the edge of the 50 cover plate 24 is likewise provided with a bead 35 which embraces the bead 34 snugly, the two forming a hinge joint and the frictional engagement between the two being depended upon to hold the plate 24 in adjusted 55 position.

In Fig. 7 a further modification of a cover plate mounting is shown, the apron having a marginal bead 36 enveloped by a marginal bead 37 formed on the cover plate 24 to constitute a hinge connection. In this case the engagement between the two beads is less snug than in the former instance and permits the plate to fall to a closed position by gravity when released by the manipulation

ing cord 38 which may extend over a pulley 65 or the like to a suitable point for manipulation. It will be noted that the upward opening movement of the plate 24 is limited by the engagement of the outer edge of the bead 37 with the shoulder formed by the 70 bead 36 of the apron 13, as indicated in dotted lines in Fig. 7.

It will be observed that in all forms of construction shown unobstructed ventilation may be provided beneath the glass and 75 yet such ventilation is readily controllable from within. The invention also provides for the escape of any moisture which condenses upon the inner face of the glass, the same being permitted when the cover plate 80 is open to run down into the passage between the chairs and thence out over the apron and through the apertures 23, the said apron protecting the wooden sill from such moisture. When the cover plate is elevated so as to leave the ventilating passages entirely unobstructed the said passages may be flushed by means of a hose, or accumulated dust removed by means of a suitable 85 suction device. 90

I claim:

1. In a store-front construction or the like, the combination of a window-sill and inner-stop, a sheet-metal apron covering said sill and the upright face and a portion of 95 the top surface of said stop, one or more chair members resting on that portion of said apron upon the sill and bearing against the stop, each of said chairs including a seat and a back adapted to accommodate 100 the lower edge of a glass-plate with the plate bearing laterally on the chair back, providing a passage beneath the edge of the glass, an outer retaining strip adapted to bear against the glass and overlying and secured to the chair or chairs, said strip being constructed not to close said passage beneath the glass, and a cover-strip hinged to that portion of the apron over the stop overlying 105 the chair back or backs and adapted to control the passage beneath the glass, substantially as described. 110

2. In a store-front construction or the like, the combination of a window-sill and inner-stop, a sheet-metal apron covering said sill and the upright face and a portion of the 115 top surface of the stop, one or more chair members resting on that portion of said apron upon the sill and bearing against the stop, each of said chair members including a seat and a back adapted to accommodate 120 the lower edge of a glass-plate with the plate bearing laterally on the chair back, providing a passage beneath the edge of the glass, an outer retaining strip adapted to bear 125 against the glass and overlying and secured to the chair or chairs, said strip being constructed not to close said passage beneath

the edge of the glass, a cover-strip hinged to that portion of the apron over the stop overlying the chair back or backs and adapted to control the passage beneath the glass, and 5 means to lock said cover-plate in adjusted positions, substantially as described.

In testimony whereof I have hereunto

signed my name in the presence of two sub-
scribing witnesses.

SILAS C. MacDOWNNEY.
